UNITED STATES PATENT OFFICE

149,623

DESIGN FOR A TEAPOT

Rolf J. Falk, Zanesville, Ohio, assignor to Shawnee
Pottery Company, Zanesville, Ohio, a corpora-
tion of Ohio

Application March 7, 1947, Serial No. 137,439

Term of patent 14 years

(Cl. D44—25)

To all whom it may concern:

Be it known that I, Rolf J. Falk, a citizen of the United States of America, residing at Zanesville, in the county of Muskingum and State of Ohio, have invented a new, original, and ornamental Design for a Teapot, of which the following is a specification, reference being had to the accompanying drawing, forming a part thereof, wherein:

Fig. 1 is a perspective view of a teapot and cover illustrating my new design;

Fig. 2, a top plan view; and

Fig. 3, a perspective view showing the side opposite from the one shown in Fig. 1.

I claim:

The ornamental design for a teapot, as shown.

ROLF J. FALK.
